DESIGN FOR A BUCKLE

William Scott Laurie, Flushing, N. Y.

Application March 27, 1936, Serial No. 61,825

Term of patent 3½ years

To all whom it may concern:

Be it known that I, William Scott Laurie, a citizen of the United States of America, residing in Flushing, Long Island, county of Queens, and State of New York, have invented a new, original, and ornamental Design for a Buckle, of which the following is a specification, reference being had to the accompanying drawing, forming part thereof.

Fig. 1 is a front view of a buckle showing my new design.

Fig. 2 is a plan view of a buckle as shown in Fig. 1.

I claim:

The ornamental design for a buckle substantially as shown.

WILLIAM SCOTT LAURIE.
